E. B. ALLEN

MASSAGE APPLICATOR

Filed Nov. 1. 1924

Inventor

Edward B. Allen

By
John F. Heim *Attorney*

UNITED STATES PATENT OFFICE.

EDWARD B. ALLEN, OF NEWTOWN, CONNECTICUT.

MASSAGE APPLICATOR.

Application filed November 1, 1924. Serial No. 747,172.

To all whom it may concern:

Be it known that I, EDWARD B. ALLEN, a citizen of the United States, residing at Newtown, in the county of Fairfield and State of Connecticut, have invented certain new and useful Improvements in Massage Applicators, of which the following is a specification, reference being had therein to the accompanying drawings.

10 This invention has for an object to provide an applicator which is especially adapted for use with soap as in softening the beard preparatory to shaving, and which may be readily cleaned and easily maintained in a sanitary condition.

Another object of the invention is to provide an applicator which will effectively soften the beard under a light rubbing action and without injury to the skin.

20 A further object of the invention is to provide an applicator having a hand-grip and a plurality of readily removable tubular elastic tips which may be replaced by a set of refill tips, supplied separately for replacement purposes, when the original tips become worn or lose their elasticity.

Still further, the invention has for an object to provide a massage applicator which will act to cleanse the pores of the skin and maintain the latter in a healthy condition.

30 It is also an object of the invention to provide an applicator which is of simplified construction enabling it to be manufactured at low cost.

35 To this attainment of the ends in view, the present applicator is constructed with two separable members which are preferably stamped in one piece from sheet-metal stock. The head is preferably apertured to receive a set of removable and replaceable tubular rubbing tips of a soft resilient material such as rubber. The tubular rubbing tips are each preferably formed separately at one end with a collar which is held seated upon the upper face of the apertured member by means of the backing member which closes the upper ends of the tips, preferably sealing and converting such tips into vacuum cups. By loosening suitable releasable connecting means such as a single thumb-screw, the back member may be readily removed, thus permitting the hollow tips to be readily cleaned by running water through them. The tips may also be removed from their supporting head.

For use as a beard softener, the applicator-head is preferably made in the shape of an isosceles triangle, the base of which is at the free or extreme end of the head and is transverse to the longitudinal axis of the 60 handle. The sides of the triangular head slope together from the ends of the base toward the handle. The rubbing tips are preferably arranged in rows parallel to the sides of the applicator-head and, by virtue 65 of this arrangement, the rubbing of the face up to the horizontal hair line in front of the ears is facilitated. The corners of the head also facilitate rubbing the spaces on the upper lip below the nose.

70 In the accompanying drawings, Fig. 1 is a side elevation of an applicator or rubbing device embodying the invention. Fig. 2 is a longitudinal section through the rubbing head of the device. Figs. 3 and 4 are, respectively, bottom and top plan views of the rubbing head, and Fig. 5 is a disassembled perspective view of the parts of the device.

75 In the embodiment of the invention illustrated, the supporting head 1 and handle 2 are blanked integral from sheet-metal stock. The blank is subjected to a forming operation in suitable dies which round over the edge 3 of the head and handle and stiffen them. The head 1 is preferably made in 80 the shape of an isosceles triangle having its base 4, Fig. 4, at right angles to the longitudinal center line of the head and handle. The sides 5, 5 of the head slope inwardly 85 toward the reduced neck 6 at the juncture 90 of the head and handle. The handle is preferably formed adjacent the neck 6 with the opposed lateral projections 7, 8 which assist the user in obtaining a firm and comfortable grip on the device, as will be explained. 95

The head 1 is shown as formed with a plurality of apertures 9, Fig. 5, in which are inserted a set of tubular rubbing tips 10 made of a soft elastic material such as rubber. The tips 10 are open at both ends and are shown formed at their base ends with enlarged portions or collars 11 which afford seats resting upon the upper surface of the head 1, as shown best in Fig. 2. A back-plate 12 of the same shape as the head 1 is 100 pressed down upon the collared ends of the tips 10 by the centrally disposed thumb-screw 13 which passes through the aperture 14 in the back-plate and is threaded into the aperture 15 in the head 1.

By tightening the thumb-screw 13 the plate 12 is caused to compress or squeeze and tightly seal the collared ends of the tips 10, thereby converting such tips into vacuum 5 rubbing tips. The back-plate 12 is formed with a downturned and curved tongue 16 which is inserted in the aperture 17 in the neck 6 to assist in properly locating the back-plate relative to the head 1. The head 10 of the screw 13 is preferably concaved as shown at 18 to serve as a rest for the fore-finger of the user; the thumb being pressed against one of the projections 7, 8 and the middle finger crooked around the other of 15 such projections. With this grip, both sides of the face may be rubbed with equal facility and without tiring effort, without changing the device from one hand to the other.

It will be observed that the tips 10 are 20 arranged in rows substantially parallel to the sides 4 and 5 of the head 1. This arrangement facilitates rubbing up to the horizontal hair line in front of the ears, and in rubbing the upper lip adjacent the nose.

25 After lathering the face, a few moments of gentle rubbing by the present applicator effectively softens the beard, enabling the user to quickly secure a smooth and close shave without the discomforts commonly attendant upon shaving, such as the pulling of the beard and the irritation of the skin by the razor. The device is also useful in massaging the face and cleansing the pores of the skin.

30 The device may be easily and thoroughly cleaned by removing the back-plate 12 and running water through the tips 10. When the latter become worn or lose their elasticity, they may be replaced by a set of refill

tips which may be sold separately from the 40 holder for replacement purposes.

It is to be understood that the present disclosure is made in an illustrative and not in a limiting sense; it being obvious that the device is susceptible of material modification 45 within the spirit and scope of the invention.

Having thus set forth the nature of the invention, what I claim herein is—

1. In a device of the class described, the combination with a plate having a plurality 50 of apertures, of a plurality of flexible tubular rubbing tips open at both ends and formed with enlarged portions at their base ends, said tips being inserted in said apertures and projected outwardly from one side of said plate and having their enlarged portions disposed in engagement with the other side of said plate, a backing member closing the enlarged ends of said tips, and readily releasable means connecting said plate and 55 backing member in assembled relation, said means permitting ready removal of said backing member for cleaning or removal of said tips.

2. In a device of the class described, the combination with a head having a plurality 60 of apertures, of a plurality of elastic rubbing tips projecting through said apertures and formed with collars at their inner ends, a backing member in engagement with the 65 collared ends of said tips, and a screw disposed substantially centrally of said head and connecting the latter with said back-plate.

In testimony whereof, I have signed my 75 name to this specification.

EDWARD B. ALLEN.
